UNITED STATES PATENT OFFICE.

ANDRÉ JULES MICHELIN, OF PARIS, FRANCE, ASSIGNOR TO MICHELIN ET CIE., OF CLERMONT-FERRAND, FRANCE, A CORPORATION OF FRANCE.

DESIGN FOR A GARAGE INFLATER.

Application filed January 24, 1929, Serial No. 29,761, and in France November 16, 1928. Term of patent 14 years.

To all whom it may concern:

Be it known that I, ANDRÉ JULES MICHELIN, a citizen of France, residing at Paris, France, have invented a new, original, and ornamental Design for Garage Inflater, of which the following is a specification, reference being had to the accompanying drawings, forming a part thereof:

Figures 1, 2, and 3 are perspective views as seen from the front, side and rear of the garage inflater showing my new design.

I claim:

The ornamental design for a garage inflater, as shown.

In testimony whereof I affix my signature.

ANDRÉ JULES MICHELIN.
